UNITED STATES PATENT OFFICE.

BENT L. WEAVER, OF HARRISBURG, PENNSYLVANIA.

ART OF MOLDING.

1,233,151.

Specification of Letters Patent. Patented July 10, 1917.

Application filed August 8, 1916. Serial No. 113,693.

To all whom it may concern:

Be it known that I, BENT L. WEAVER, a citizen of the United States, residing at Harrisburg, in the county of Dauphin and State of Pennsylvania, have invented certain new and useful Improvements in the Art of Molding, of which the following is a specification.

My invention relates to improvements in the art of molding. The object of my invention is to provide a novel and improved art or process, by the aid of which patterns heretofore too long or too large to be molded in molding machines and heretofore requiring skilled labor to mold them, may be molded in separate sections on a molding machine with unskilled labor; and thereafter secured together to form a complete mold of the entire pattern to be cast.

With this object in view my invention consists of the novel and improved art or process of molding hereinafter fully described and claimed.

In the drawings,

Figure 1 is a perspective view of a flask having a mold formed therein, and by the aid of which my improved art or process may be performed.

Fig. 2 is a perspective view of one of the sections of the drag of the flask, having a section of a mold formed therein.

Fig. 3 is a plan view of the complete drag of the flask having a sectional mold of a complete pattern formed therein, and showing the sections of the complete pattern placed within the corresponding sections of the mold therein, for the purpose of illustrating the relationship between the pattern sections and the mold sections.

Fig. 4 is a transverse section of the flask and mold and pattern therein, on line 4—4 of Fig. 1.

Fig. 5 is a longitudinal section of the flask and mold and pattern therein, on line 5—5 of Fig. 1.

Referring to the drawings, the flask comprises a cope 2 and a drag 3, separable from each other on a horizontal plane and detachably secured together by means of bolts 6 which extend through outwardly projecting flanges of the cope and drag.

The cope 2 comprises side walls 7 and end walls 8 which abut against the ends of the side walls 7 and which are secured thereto by means of bolts 9. The side walls 7 are

each formed of separable sections 10 which are in horizontal alinement with each other and which are detachably secured together by suitable bolts 11 which extend through flanges on the sections 10. The cope 2 is provided with suitably spaced bars 12 which extend between the opposite sections 10 of the side walls 7 thereof and which are secured thereto and which serve to stiffen the flask and strengthen the body of sand contained therein.

The drag 3 comprises side walls 13 and end walls 14 which abut against the ends of the side walls 13 and which are secured thereto by suitable bolts 15. The side walls 13 of the drag 3 are each formed in separable sections 16 which are in horizontal alinement with each other and which are detachably secured together by means of bolts 17 extending through flanges on the sections 16. The drag 3 is provided with a sectional bottom wall 18 each section 19 of which extends between two oppositely disposed sections 16 of the two side walls 13. The sections 19 of the bottom wall 18 are provided with suitable strengthening ribs, as shown, and are secured to the sections 16 of the side walls 13 of the drag 3 by means of bolts 20 which extend through the sections of the bottom wall 18 and the flanges on the sections 16 of the side walls 13. The bottom wall 18 serves to support the sand within the drag 3.

The cope 2 may be divided into separate sections at the joints between the sections 10 of its side walls 7, each two oppositely disposed sections 10 of the side walls 7 forming the side walls of a section of the cope; and the drag 3 also may be thus divided into separate sections at the joints between the sections 16 of its side walls 13, each two oppositely disposed sections 13 forming the side walls of a section of the drag. The sections 10 of the side walls 7 of the cope 2 register with and are in vertical alinement with the sections 16 of the side walls 13 of the drag 3; and the sections of both the cope and the drag are separable from each other on the common vertical planes indicated by the lines 21—21 in Fig. 3. The end walls 8 of the cope 2 register with and are in vertical alinement with the end walls 14 of the drag 3, as shown; and the end walls 8 and 14 of the cope 2 and drag 3, respectively, are provided with outwardly-projecting 110

trunnions 22 for a purpose hereinafter appearing.

It will be observed that the sections 10 of the side walls 7 of the cope 2 are duplicates 5 of each other and of the sections 16 of the side walls 13 of the drag 3, so that one section may be interchanged or may be substituted for another section of either wall 7 or 13, as desired; and it will also be observed 10 that the end walls 8 of the cope 2 are duplicates of the end walls 11 of the drag 3 so that the said end walls may be interchanged or substituted one for another.

The sections 10 and 16 of the side walls 7 15 and 13 of the cope 2 and drag 3, respectively, are provided with holes 23 which are adapted to register with each other and to receive suitable dowel pins, not shown, for the proper setting of the sections of the flask 20 with relation to each other and with relation to the parts of a molding machine.

My improved art of molding by the aid of the flask hereinbefore described is as follows:

25 I have herein illustrated a pattern of a locomotive frame extending through the three sections of the drag 3 and indicated at 24, in Figs. 2 and 3. This pattern is separated into three sections on vertical planes corresponding with the lines 21 in Fig. 3, the sections being separable from each other and the corresponding end faces of the pattern sections abutting against each other at the planes or lines 21, when forming the complete pattern to be molded. In making the mold of this pattern, the cope and the drag of the flask hereinbefore described are separated, the sections thereof are also separated on the vertical planes 21—21 and the sections 35 16 of the bottom wall are removed from the drag. This being done, the first section of the drag is provided with a temporary end wall 25 which abuts against the ends of the sections 16 forming its side walls which previously abutted against other similar sections of the side walls 13 of the drag 3, the temporary end wall 25 being a duplicate of the end wall 14. The first section of the pattern 24 for the mold is now properly placed 40 on the mold board or pattern frame of a molding machine, and the first section of the drag, with the temporary end wall 25, as illustrated in Fig. 2, is then properly placed on the mold board of the molding machine 45 and around the section of the pattern 24 with the temporary end wall 25 against the end of the pattern section which registers with a similar end wall of another pattern section in forming the complete mold cavity, as 50 illustrated, at 24^a, by the mold formed in the sand in Fig. 2, sand is introduced to the drag section thus placed, and the mold of the first section of the locomotive frame is formed within the drag section, in the usual 55 manner with the aid of the molding ma-

chine. A section 19 of the bottom wall 18 is then placed upon the top of the drag section on the machine and bolted thereto. The drag section is then inverted on the trunnions 22 and the pattern of the first section of the mold is withdrawn from the drag section, leaving the mold 24^a therein, as illustrated in Fig. 2. The first drag section is then placed upon a suitable support and the temporary end wall 25 is removed therefrom. The second section of the pattern of the mold is now placed upon the mold board of the molding machine, temporary end walls similar to the wall 25 are now bolted to the ends of the side wall sections 16 of the second section of the drag 3 to temporarily close the ends thereof. This second section of the drag is now placed on the molding machine around the second section of the pattern with the temporary end walls against the ends of the pattern section which register with similar end walls of the adjacent sections in forming the complete pattern and the second section of the pattern is molded therein similar to the molding of the first pattern section, as previously described. The second drag section is now removed from the molding machine, the temporary end walls are removed therefrom and it is placed on a support adjacent to the first drag section and bolted thereto with the mold of the second pattern section in registry with the mold of the first pattern section, as shown in Fig. 3. The mold of the third and final pattern section is now formed in the third and final section of the drag, similarly to the formation of the mold of the first pattern section, as previously described, and the final drag section is bolted to the second drag section with the mold of the final pattern section in registry with the mold of the second pattern section, and the mold of the entire pattern in the drag 3 is then complete, as shown in Fig. 3.

The side and end walls of the cope 2 are exactly like the side and end walls of the drag 2; and, in making the cope section of the mold, the operation of making the drag section, previously described, is followed with the exception that no bottom plate sections are secured to the cope sections and no pattern sections are molded in the sand in the cope sections. After the complete cope section 2 has been formed it is placed upon the drag section 3 and bolted thereto, forming the complete mold, as shown in Fig. 1, 110 115 120 The sand of the cope section of the mold is provided with suitable risers or heads R and also with a suitable pouring gate G for the introduction of the molten metal to the mold.

The sections of the side walls of the cope 2 and drag 3 are not only interchangeable but they are reversible. Also the end walls of the cope 2 and drag 3 are not only interchangeable but reversible. It will thus be seen, that either a cope section or a drag 125 130

section of a flask may be readily constructed with any of the end walls or side wall sections of the entire flask.

The flask may be constructed any desired length to suit different patterns, by employing more or less of the flask sections as the circumstances of the particular case may require.

I claim:

- 10 1. The art of molding which consists in forming a pattern in separable sections having corresponding end faces and which form a complete pattern when the corresponding end faces thereof are brought into registry with each other, separately placing the pattern sections within suitable mold forming flasks with the said end faces against removable walls of the flasks which are arranged opposite to the other walls of the flasks, placing sand within said flasks and forming separate mold sections of the pattern sections, removing the pattern sections from the mold sections, removing the said removable walls from the mold sections, and assembling the separately formed mold sections with the molds of the pattern sections therein in registry with each other and thereby forming a mold of the complete pattern.
- 20 2. The art of molding which consists in forming a pattern in separable sections having corresponding end faces and which form a complete pattern when the corresponding end faces thereof are brought into registry with each other, separately placing the pattern sections within suitable mold forming flasks with the said end faces against removable

walls of the flasks which are arranged opposite to other walls of the flasks, placing sand within said flasks and forming separate mold sections of the pattern sections, removing the pattern sections from the mold sections, removing the said removable walls from the flasks, and securing the said flasks together with the separately formed mold sections therein in registry with each other and thereby forming a mold of the complete pattern.

3. The art of molding which consists in forming a pattern in separable sections having corresponding end faces and which form a complete pattern when the corresponding end faces thereof are brought into registry with each other, separately placing the pattern sections upon suitable supports and within suitable mold forming flasks which surround the sections and extend upwardly from the supports and which have removable walls against the said end faces of the pattern sections, placing sand within said flasks and forming separate mold sections of the pattern sections, placing mold supporting plates upon said flasks and securing them thereto, inverting said flasks and said supports, removing said supports and said removable walls from said flasks, and securing the said flasks together with the separately formed mold sections therein in registry with each other and thereby forming a mold of the complete pattern.

In testimony whereof I affix my signature hereto.

BENT L. WEAVER.
